UNITED STATES PATENT OFFICE

GEORGE D. GARDNER, OF SAN JOSE, CALIFORNIA, ASSIGNOR, BY MESNE ASSIGNMENTS, TO SPRAGUE-SELLS CORPORATION, OF HOPESTON, ILLINOIS, A CORPORATION OF DELAWARE

BOX-CHAMFERING MACHINE AND CUTTER

Application filed July 22, 1925. Serial No. 45,152.

This invention relates particularly to a machine for chamfering the corners of wooden boxes.

An object of the invention is to provide an apparatus through which boxes may be passed so as to remove the sharp corners thereof, which are dangerous to individuals handling said boxes, and which will also prepare the boxes so that the same may be more readily held together when wrapped with string, wire or the like.

A further object of the invention is to provide a box chambering machine provided with a plurality of cutters thereon so arranged that the cutters are self-adjusting and will compensate relative to each other when the boxes are of various or irregular sizes or where the contour is irregular.

A still further object of the invention is to provide a box chamfering machine through which wooden boxes may be automatically moved and held in a pre-determined path of movement during the chamfering operation and a pre-determined depth of the box edges cut off during the chamfering operation.

Other objects of the invention relate to a box chamfering machine in which skew cutters are used for chamfering the box corners and to a complete apparatus, of the character to be hereinafter described that is superior in point of simplicity, inexpensiveness of construction, positiveness of operation, and facility and convenience in use and general efficiency.

In this specification and the annexed drawings, the invention is illustrated in the form considered to be the best, but it is to be understood that the invention is not limited to such form, because it may be embodied in other forms, and it is also to be understood that in and by the claims following the description, it is desired to cover the invention in whatsoever form it may be embodied.

In the accompanying two sheets of drawings

Fig. 1 represents a side elevation of a box chambering machine constructed in accordance with my invention.

Fig. 2 is a plan view of Fig. 1.

Fig. 3 is an end elevation of Fig. 1.

Fig. 4 is an enlarged cross section taken through Fig. 1 on the line 4-4.

Fig. 5 is a front elevation of one of the skew cutters.

Fig. 6 is a section taken through Fig. 5 on the line 6-6.

Fig. 7 is a fragmentary section through an edge of one of the cutters shown in Fig. 6.

In the invention described in the following specification, I have devised a machine for chamfering or cutting off four corners of a wooden box simultaneously in one operation.

In the shipment of canned goods, dried fruit and other commodities in small wooden boxes, or cases, a very serious and costly handicap has always been experienced through breakage in bottoms and lids due to unevenness in material, caused by either shrinkage or expansion in the same. It is found that when the box has been assembled, packed and lidded, that there is a considerable amount of box material over-hanging the sides of the box which, when an attempt is made to handle and stack, results in a break whenever pressure, or a blow, is brought on the overhanging portion. This break will not occur on the line of the box side, but in nearly all cases starts at the point where the nearest nail is driven—from one to two inches from the side. When this break occurs an opening is started through which the contents may, as in dried fruits especially, escape or be tampered with. As a result of this condition transportation companies will not receive and be responsible for the contents and insist that these boxes be put in proper condition, which is called cooperage.

To obviate cooperage it has been common practice to remove protruding or uneven box edges and to slightly bevel or chamfer the same to an angle receding from the box side, thus producing a smooth package with no sharp corners which also may be, if desired, more readily strapped, tied or wrapped with wire or other materials to help hold the box firmly together.

In detail the construction illustrated in the drawings comprises a frame 1 having a sub-

stantially horizontal top surface 2. At the opposite ends of the frame top 2 I have mounted the respective pairs of bearings 3 and 4, and in the bearing 3 a shaft 5 is journaled, and in the bearing 4 a shaft 6 is journaled. A sprocket wheel 7 is fixed on the shaft 5 and a sprocket wheel 8 is fixed on the shaft 6. The sprocket wheels 7 and 8 are fixed on the respective shafts 5 and 6 so as to lie substantially on the longitudinal center of the frame top 2. Around the sprocket wheels 7 and 8 I have passed an endless chain 9, which at regular intervals throughout its entire length is provided with upstanding lugs 10 for the purpose of pushing the boxes, to be hereinafter described, through the cutters. The upper half of the endless chain 9 moves over a guide member 11 which extends substantially the full length of the frame top 20 between the sprockets 7 and 8. The guide member 11 serves to keep the sprocket chain 9 on a substantially level path of movement. The guide member 11 is supported at each of its opposite ends on brackets 12 and 13, which brackets are secured on the frame top 2. On opposite sides of the upper half of the chain 9, a pair of guide strips 14 and 15 are arranged and secured at their opposite ends to the brackets 12 and 13. The upper surface of the auxiliary guide strips 14 and 15 lies substantially flush with the upper surface of the endless belt 9. A box placed on the guide strips 14 and 15 would be moved lengthwise thereon by the lugs 10 on the chain 9 engaging an end of the box.

In the center of the frame top 2 I have mounted a housing or frame structure 20 in which the box chamfering cutters are rotatably journaled. The housing 20 is open at each of its opposite ends in order to receive a box to be chamfered at one end and to discharge the said chamfered box out of the opposite end thereof. Adjacent the intake end of the housing 20 a shaft 21 is journaled at its opposite ends and bearings 22 and 23 mounted on opposite sides of the housing 20. The bearings 22 and 23 are provided with antifriction races, and suitable packing glands to retain lubricant on the bearing parts. A cutter 24 is fixed on the shaft 21, on one side of the sprocket chain 9, said cutter 24 being fixedly keyed to the shaft 21. A companion cutter 25 is slidably splined at 26 on the shaft 21 on the opposite side of the chain 9. The cutters 24 and 25 face each other and the cutter 25 is arranged on the shaft 21 so that it may move axially toward or from the cutter 24. A stop 27 restricts axial movement of the cutter 25 while movement of the cutter 25 in the opposite direction is taken care of by a compression spring 28 interposed between the cutter 25 and bearing 23. The particular form of the structure for housing the spring 28 or other springs on the cutters may vary with the form of the machine and if desired

may be entirely closed as shown at 29, so as to form a lubricant reservoir. An end of the shaft 21 extends beyond the housing 20 and is provided with a pulley 30 thereon. A prime mover 31 is also secured to the shaft 21 for the purpose of imparting rotative movement thereto. The opposite end of the shaft 21 is provided with a worm 32 thereon which meshes with a worm wheel 33 mounted on a shaft 34 journaled at its opposite ends in the bearings 35 and 36, respectively, mounted on the frame 1. The end of the shaft 34 in the bearing 36 is provided with a bevel gear 37 thereon which meshes with a bevel gear 38 secured to the end of the sprocket shaft 6. Thus rotative movement from the prime mover 31 is transmitted through the drive shaft 21 and through the interposed gearing to the sprocket shaft 6, by which continuous movement of the endless chain 9 is obtained in unison with the cutters.

An arm 40 is journaled at its lower end on the bearing 22 and a complementary arm 41 is journaled at its lower end on the opposite bearing 23. The free ends of the arms 40 and 41 are joined together by a cross shaft 42, the opposite ends of which project through slots 43 provided in the opposite sides of the housing 20 adjacent the upper side thereof. Suitable nuts 44 are adjustably mounted on each of the opposite ends of the shaft 42. The nuts are adapted to be advanced into contact with the opposite faces of the housing 20 adjacent the arcuate slots 43 for positioning the said arms 40 and 41 in any selected position. An anti-friction bearing 45 is mounted near the upper end of the arm 40 and a similar anti-friction bearing 46 is mounted near the upper end of the complementary arm 41. A shaft 47 is journaled at its opposite ends in the bearings 45 and 46 and an end of the said shaft 47 projects outwardly through an arcuate slot 48 provided in one side of the housing 20. The projecting end of the shaft 47 has a pulley 49 thereon in registered alignment with the pulley 30 on the lower shaft 21. A cutter 50 is mounted to slide axially on the shaft 47, said cutter 50 being arranged in substantial alignment with the cutter 24 mounted on a corresponding side of the lower shaft 21. A compression spring 51 is interposed between the cutter 50 and the bearing 45 so as to advance the cutter 50 toward the center of the machine, movement of the cutter 50 being limited by a stop collar 52. A complementary cutter 53 is slidably splined on the shaft 47 facing the cutter 50 and said cutter 53 is adapted to be moved axially on the shaft 47. A compression spring 54 is mounted behind the cutter 53 so that the said cutter may move lengthwise of the shaft 47 within limits restricted by the stop collar 53 and the compression spring 54. The cutter 53 on the shaft 47 is arranged

in substantial alignment with the corresponding cutter 25 on the lower shaft 21.

The two cutters 24 and 25 on the lower shaft and the cutters 50 and 53 on the upper shaft are thus arranged so as to bound a substantially rectangular opening. A belt 57 is passed around the pulleys 49 and 30 so that each of the shafts 47 and 21 will operate together and at the same rate of speed. A pair of side guide strips 59 and 60 are supported within the housing 20 on opposite sides of the sprocket chain 9 and substantially midway between the upper and lower cutter shafts 47 and 21. The guide strips 60 are adjusted in and out on one side of the chain 9 so as to compensate for irregularities in the size of the boxes being chamfered. A top guide strip 61 is adjustably suspended from the upper side of the casing 20. The bottom 20 guides 14 and 15, side guides 59 and 60, and the upper guide 61 form a path in which a box having its corners chamfered will move, and said guides are so arranged that differences in the sizes of boxes passing therethrough may be compensated for without in anywise affecting the operation of the corner cutters.

I have arranged the cutters on the shafts so that one cutter is fixed while the remaining 30 three cutters are axially adjustable on the respective shafts so that in the event the boxes being chamfered are not of a uniform size, the cutters will automatically adjust themselves with relation to the fixed cutters and 35 to each other, so that substantially the same depth of cut will be taken from each corner of the box irrespective of how much the width of the boxes passing through the machine may vary. Boxes of varying heights may 40 have the upper corners thereof chamfered with facility, by moving the upper cutter shaft 47 in its arcuate slot 48, thus raising or lowering the cutter shaft 47 above the sprocket chain 9.

The cutters 24, 25, 50 and 53 are each provided with a plurality of cutting teeth 70 thereon, each of which does not radiate from the axis thereof, but are offset relative thereto. The cutters are technically known as 50 bevelled skew cutters, on account of the manner in which the teeth are formed thereon. I have found that the corner chamfering of boxes cannot be successfully done without utilizing skew cutters of the character I have shown, as ordinary bevel cutters do not function with any degree of efficiency.

The cutter, or cutters, which I use are of new and novel design, being a beveled blank 60 of desired cutting angle having a plurality of what are technically called skew teeth cut therein, each tooth having its cutting edge set at a skew or angle, to a radial line in order to produce a slicing, cutting effect. 65 Each tooth is also undercut to provide a

means of escape for the material removed and to produce the tooth edge.

This novel shape has been found to be the most efficient design and is not confined alone to chamfering, but materials may be used in 70 various operations by changing the cutting angle to any desired shape or form.

By the use of my invention, boxes may be placed on the endless belt and fed through the cutters and the four lengthwise corners of the box cut therefrom without the necessity of the machine operator adjusting or otherwise manipulating the apparatus with each box which may be passed therethrough. My apparatus is entirely automatic in its 75 operation and in efficient and effective manner will cause the corners of a box to be removed without let up or delay.

Having thus described this invention, what I claim and desire to secure by Letters Patent is:

1. A machine for chamfering the corners of boxes comprising a base; an endless conveyor to move boxes over said base; guides arranged adjacent said endless conveyor to regulate the path of movement of the boxes; a pair of spaced beveled cutters journaled in axial alinement on opposite sides of said base, and arranged in registry with the under faces of the boxes passing through the guides to bevel the opposite under corners of the boxes; a pair of support arms, each having one end thereof pivotally mounted adjacent one of the aforementioned cutters; a pair of spaced beveled cutters journaled in axial alinement on the free ends of said arms and substantially co-planar with the first mentioned cutters, and arranged in registry with the opposite upper corners of the boxes passing through said guides to bevel the opposite upper corners of the boxes; and means for actuating each of said cutters and endless belt.

2. A machine for chamfering the corners of boxes comprising a base; an endless conveyor to move boxes over said base; guides arranged adjacent said endless conveyor to regulate the path of movement of the boxes; a pair of spaced beveled cutters journaled in axial alinement on opposite sides of said base, and arranged in registry with the under faces of the boxes passing through the guides to bevel the opposite under corners of the boxes; a pair of support arms, each having one end thereof pivotally mounted adjacent one of the aforementioned cutters; a pair of spaced beveled cutters journaled in axial alinement on the free ends of said arms and substantially co-planar with the first mentioned cutters, and arranged in registry with the opposite upper corners of the boxes passing through said guides to bevel the opposite upper corners of the boxes; and a common means for rotating each of said cutters in unison and for actuating said endless belt.

3. A machine for chamfering the corners of boxes comprising a base; an endless conveyor to move boxes over said base; guides arranged adjacent said endless conveyor to regulate the path of movement of the boxes; a pair of spaced beveled cutters journaled in axial alinement on opposite sides of said base, and arranged in registry with the under faces of the boxes passing through the guides to bevel the opposite under corners of the boxes; a pair of support arms, each having one end thereof pivotally mounted adjacent one of the aforementioned cutters; a pair of spaced beveled cutters journaled in axial alinement on the free ends of said arms and substantially co-planar with the first mentioned cutters, and arranged in registry with the opposite upper corners of the boxes passing through said guides to bevel the opposite upper corners of the boxes; means for adjusting the space between the first mentioned and second mentioned pair of cutters; and means for actuating each of said cutters and endless belt.

4. A machine for chamfering the corners of boxes comprising a base; an endless conveyor to move boxes over said base; guides arranged adjacent said endless conveyor to regulate the path of movement of the boxes; a pair of spaced beveled cutters journaled in axial alinement on opposite sides of said base, and arranged in registry with the under faces of the boxes passing through the guides to bevel the opposite under corners of the boxes; a pair of support arms, each having one end thereof pivotally mounted adjacent one of the aforementioned cutters; a pair of spaced beveled cutters journaled in axial alinement on the free ends of said arms and substantially co-planar with the first mentioned cutters, and arranged in registry with the opposite upper corners of the boxes passing through said guides to bevel the opposite upper corners of the boxes; means for adjusting the space between the first mentioned and second mentioned pair of cutters; and a common means for rotating each of said cutters in unison and for actuating said endless belt.

5. A machine for chamfering the corners of boxes comprising a base; an endless conveyor to move the boxes over said base; guide strips adjustably mounted on said base on opposite sides of and over said endless conveyor to form an open ended passage way for the boxes; a pair of spaced cutters journaled in axial alinement on opposite sides of said base and arranged in registry with the under faces of the boxes passing through the guides to bevel the opposite under corners of the boxes; a pair of spaced cutters journaled in axial alinement on opposite sides of said base, substantially co-planar with the first mentioned cutters, and arranged in registry with the upper faces of the boxes passing through said guides to bevel the opposite upper corners of

the boxes; means for adjusting the space between the first mentioned and second pair of cutters; and means for actuating each of said cutters and endless belt.

6. A machine for chamfering the corners of boxes comprising a base; an endless conveyor to move the boxes over said base; guide strips adjustably mounted on said base on opposite sides of and over said endless conveyor to form an open ended passage way for the boxes; a pair of spaced cutters journaled on opposite sides of said base and arranged in registry with the under faces of the boxes passing through the guides; arms journaled on said base; a shaft rotatably mounted in the free ends of said arms; a pair of cutters mounted adjacent opposite ends of said shaft, substantially co-planar with said first mentioned cutters, and arranged in registry with the upper faces of the boxes passing through said guides; and means for actuating each of said cutters and endless belt.

7. A machine for chamfering the corners of boxes comprising a base; an endless conveyor to move the boxes over said base; guide strips adjustably mounted on said base on opposite sides of and over said endless conveyor to form an open ended passage way for the boxes; a pair of spaced cutters journaled on opposite sides of said base and arranged in registry with the under faces of the boxes passing through the guides; arms journaled on said base; means to adjust the position of the free ends of said arms relative to said base; a shaft rotatably mounted in the free ends of said arms; a pair of cutters mounted adjacent opposite ends of said shaft, substantially co-planar with said first mentioned cutters, and arranged in registry with the upper faces of the boxes passing through said guides; and means for actuating each of said cutters and endless belt.

8. A machine for chamfering the corners of boxes comprising a base; an endless conveyor to move the boxes over said base; guide strips adjustably mounted on said base on opposite sides of and over said endless conveyor to form an open ended passage way for the boxes; a shaft revolvably mounted in said base substantially parallel with the plane of movement of said endless conveyor; a pair of cutters mounted on said shaft in registry with the under faces of boxes passing through the guides, one of said cutters being movable axially relative to the other cutter to accommodate boxes of varying widths; arms journaled on said base; a shaft rotatably mounted in the free ends of said arms; cutters adjustably mounted on said last mentioned shaft substantially co-planar with the cutters on said first mentioned shaft and arranged in registry with the upper faces of the boxes passing through said guides; and means for effecting movement of each of said cutter shafts and endless belt.

9. A machine for chamfering the corners of boxes comprising a base; an endless conveyor to move the boxes over said base; guide strips adjustably mounted on said base on opposite sides of and over said endless conveyor to form an open ended passage way for the boxes; a shaft revolvably mounted in said base substantially parallel with the plane of movement of said endless conveyor; a pair of cutters mounted on said shaft in registry with the underfaces of boxes passing through the guides, one of said cutters being movable axially relative to the other cutter to accommodate boxes of varying widths; arms journaled on said base; a shaft rotatably mounted in the free ends of said arms; cutters adjustably mounted on said last mentioned shaft substantially co-planar with the cutters on said first mentioned shaft and arranged in registry with the upper faces of the boxes passing through the said guides; means to adjust the position of the free ends of said arms to regulate the placement of the cutters on the second mentioned shaft to accommodate boxes of varying heights; and means for effecting movement of each of said cutter shafts and endless belt.

10. In a machine for chamfering corners of an object, a pair of axially alined rotatably mounted beveled cutters spaced to trim opposite corners of the object, a second pair of axially alined rotatably mounted beveled cutters spaced from the first pair of cutters and spaced from each other to trim other opposite corners of the object, means for mounting both cutters of one pair for axial movement, means for mounting a cutter of the other pair for axial movement, means for yieldably holding the axially movable cutters in position, and means for rotating the cutters.

11. In a machine for chamfering corners of an object, a rotatably mounted cutter for trimming one corner of the object, a second rotatably mounted and yieldably held cutter spaced from the first cutter and adjustably movable about the axis of the first cutter for trimming an opposite corner of the object, said second cutter being adjustable to accord with one dimension of the object and yieldable to accord with another dimension thereof, and means for rotating the cutters.

12. In a machine for chamfering corners of an object, a yieldably held rotatably mounted cutter for trimming one corner of the object, an arm adjustable about the axis of the first cutter, a second yieldably held cutter spaced from the first cutter and journaled in the arm for trimming an opposite corner of the object, said arm being adjustable to accord with one dimension of the object and said cutters being yieldable to accord with other dimensions thereof, and means for rotating the cutters.

13. In a machine for chamfering corners

of an object, a pair of rotatably mounted cutters spaced to trim opposite corners of the object, a second pair of rotatably mounted cutters spaced from the first pair of cutters and spaced from each other to trim other opposite corners of the object, one of the cutters of each pair being yieldably held against axial movement to automatically accord with one dimension of the object, means for adjustably positioning the second pair of cutters relative to the first pair to accord with another dimension of the object, and means for rotating the cutters.

14. In a machine for chamfering corners of an object, a pair of axially alined rotatably mounted cutters spaced to trim opposite corners of the object, a second pair of axially alined rotatably mounted cutters spaced from the first pair of cutters and spaced from each other to trim other opposite corners of the object, means for adjustably positioning the second pair of cutters about the axis of the first pair to accord with one dimension of the object, means for yieldably holding three of the cutters to accord with other dimensions of the object, and means for rotating the cutters.

15. In a machine for chamfering corners of an object, a shaft journaled for rotation in an axis substantially parallel to a surface of the object, a pair of cutters spaced to trim opposite corners of the object and fixed on the shaft for rotation therewith, a second shaft journaled for rotation and adjustably mounted for movement about the axis of the first shaft to accord with one dimension of the object, a pair of cutters spaced to trim opposite corners of the object and fixed for rotation with the second shaft, one of the cutters in the first mentioned pair and both of the cutters in the second mentioned pair being yieldably held against axial movement to accord with other dimensions of the object, and means for rotating the shafts.

In testimony whereof, I have hereunto set my hand at San Francisco, California, this 30th day of June, 1925.

GEORGE D. GARDNER.
